UNITED STATES PATENT OFFICE.

JUDSON E. HILL AND WILLIAM H. DEACON, OF PHILADELPHIA, PA.,
ASSIGNORS TO JAMES H. GAY, OF SAME PLACE.

DESIGN FOR CARPETS.

Specification forming part of Design No. 9,723, dated January 30, 1877; application filed January 9, 1877.
[Term of Patent 3½ years.]

To all whom it may concern:

Be it known that we, JUDSON E. HILL and WILLIAM H. DEACON, of the city and county of Philadelphia, State of Pennsylvania, have invented and produced a new and original Design for Carpets, of which the following is a specification:

The nature of our design is fully represented in the accompanying photographic illustration, to which reference is made.

We claim as our invention—

The configuration of the design hereunto annexed, when applied to carpeting.

JUDSON E. HILL.
WILLIAM H. DEACON.

Witnesses:

JAMES BROWN,
JAMES GIBSON.
